UNITED STATES PATENT OFFICE.

KARL STENMAN, OF NEW YORK, N. Y.

DESIGN FOR A FRAME FOR CIGAR-CUTTERS.

42,066.

Specification for Design.

Patented Dec. 26, 1911.

Application filed July 11, 1910. Serial No. 571,515. Term of patent 7 years.

To all whom it may concern:

Be it known that I, KARL STENMAN, a citizen of the United States, residing at New York, in the county of New York and State of New York, have invented a new, original, and ornamental Design for a Frame for Cigar-Cutters, of which the following is a specification.

This invention relates to new and ornamental designs for a frame for cigar cutters and the general object of the invention is to improve the ornamental appearance of cigar cutters of the type illustrated in the accompanying drawings, in which,

Figure 1 is a front elevation of the improved design, and Fig. 2 is a side elevation thereof.

Referring to the accompanying drawings

illustrating the improved design 1 denotes the casing of the cutter, and 2 the cigar tip receiving cup or guide. The cup is flared outwardly to present an artistic appearance. The casing 1 is attached to two ornamental supports 3 and 4, which are connected to a ring 5 and are in the form of ornamental scroll work.

I claim:—

The ornamental design for a frame for cigar cutters as shown, and described.

In testimony whereof I affix my signature in presence of two witnesses.

KARL STENMAN.

Witnesses:

WERNER J. FREELAND,
CHAS. E. STENMAN.
